UNITED STATES PATENT OFFICE.

JAKE L. RANNEY, OF MACEDONIA, OHIO.

MACHINE FOR WASHING CANS AND THE LIKE.

940,060.

Specification of Letters Patent. Patented Nov. 16, 1909.

Application filed May 16, 1907. Serial No. 374,078.

To all whom it may concern:

Be it known that I, JAKE L. RANNEY, a citizen of the United States, resident of Macedonia, county of Summit, and State of Ohio, have invented a new and useful Improvement in Machines for Washing Cans and the Like, of which the following is a specification, the principle of the invention being herein explained and the best mode 10 in which I have contemplated applying that principle, so as to distinguish it from other inventions.

My invention relating, as stated, to washing machines, is designed more particularly 15 for use in connection with the washing of vessels, such as cans, and particularly milk cans. That a considerable portion of the trouble experienced by dairymen and dealers in milk with their customers is attributable 20 to improper or faulty cleansing of the vessels employed in connection with the handling of the commodity in question cannot be gainsaid. Of all the vessels thus employed, perhaps none are more difficult to 25 preserve in a proper cleanly state than the cans in which milk is handled in bulk. So far as I am aware, among all the numerous washing devices that have been provided for handling various sorts of vessels, none have 30 been brought forth with a view to providing proper facilities for the washing of this particular vessel or can.

The object of my invention is, then, the provision of means for the thorough and 35 expeditious cleansing, and also sterilization, of vessels of the class in hand.

To the accomplishment of this and related objects, said invention consists of the means hereinafter fully described and particularly set forth in the claims.

The annexed drawings and the following description set forth in detail certain mechanism embodying the invention, such disclosed means constituting, however, but one 45 of various mechanical forms in which the principle of the invention may be used.

In said annexed drawings: Figure 1 is a vertical central cross-section of one form of machine embodying my several improvements; Fig. 2 is a plan view of such machine; Fig. 3 is a horizontal cross-section thereof taken on the line 3—3, Fig. 1; Fig. 4 is a vertical central cross-section of the means employed for supplying liquid to the 50 interior of the vessel being washed, together with certain appurtenant parts; and Fig. 5

is a detail view of a portion of the brush employed in washing such vessel's interior.

Having regard, then, to the several figures just described, A will be seen to designate 60 the frame of the machine shown as being constructed of timbers, although this is wholly immaterial, being a matter of convenience merely. Suitably supported in the base of such frame is a vertically disposed 65 hollow conduit or pipe B that is designed to be so mounted as to be stationary with respect to the frame, being supported at its lower end upon a block a. Upon such pipe are mounted both the brushes, hereinafter 70 more fully to be described, and the rotary support C designed to receive the vessel to be washed, the latter resting upon a suitable bearing provided upon a transverse portion of frame A, as shown in Fig. 1. Such pipe 75 further serves as a means for conducting within the interior of the vessel being washed the necessary liquid for cleansing the same. To the latter end, connection is had with a suitable source of liquid supply, by 80 means of another pipe B', the flow of liquid therethrough being controlled by a suitable valve b. Ordinarily, of course, hot water will be the liquid thus employed. In order to suitably direct and distribute the water 85 within the can, the upper end of pipe B is provided with a nozzle or rose b', of which one specific form of construction and mode of attachment is clearly shown in Fig. 4. It 90 is desirable, in order to sterilize the vessels, to employ in connection with such hot water, the primary purpose of which is to cleanse the vessel's walls, live steam. For the purpose of furnishing this steam, a second pipe b'', having suitable exterior connection, is 95 disposed within aforesaid pipe B forming the fixed support just described. The discharge end b''' of this pipe will be seen, Figs. 1 and 4, to project beyond the rose b' forming the terminal portion of pipe B. 100

Referring now to the brush designed for cleansing the interior walls of the vessel, this will be seen to consist in the form shown, Figs. 1 and 3, of two independent vertically disposed sections D, pivotally mounted at the outer ends of arms b' radially extending from the axial support provided by pipe B. The way in which these radial arms are secured to such supporting pipe is clearly shown in Figs. 1 and 4, it being designed 105 110 that they shall be non-rotatably or rigidly held in respect thereto. The brush sections

D are desirably provided with inwardly extending arms *d* wherewith pivotal connection is had with aforesaid radial projecting supporting arms *b*⁴ in order that a greater amount of variation in the lateral adjustment of the brushes may be had.

In order that the lower radially inset portion *d*' of each brush member D may be capable of sufficient retraction, since it lies disposed very nearly in a line with the pivotal axis about which such member swings, I offset this lower portion from the main body of the brush, Fig. 5. By this construction, while the lower brush can be held closely against the wall of the can neck in the open or expanded condition of the brush, it is retracted sufficiently to easily clear such neck when it becomes necessary to remove the can at the conclusion of the washing operation.

In view of the previous description of the manner in which the brushes D, are supported, it will be seen that they are in effect oscillatorily mounted on axes parallel with the supporting pipe B. For the purpose of swinging such brush sections about their axes of oscillation, a sleeve *b*⁵ is rotatably mounted upon the lower portion of the central supporting pipe, such sleeve being provided at its upper end with projecting arms *b*⁶ similar to those borne by the pipe. Links *d*² connecting the ends of these arms with the inwardly projecting arms *d*, whereby the brush sections are pivotally supported, are obviously adapted to effect oscillation of the sections upon rotation of the sleeve *b*⁵. To effect rotation thereof and consequent adjustment of the brush sections, a lever *b*⁷ is mounted upon the lower end of the sleeve, and is suitably connected by means of rods *b*⁸, *b*⁹ and bell-crank *b*¹⁰ with the hand-lever *b*¹¹ located where most convenient at one side of the machine frame A. The levers and connections in question are of such proportions as to enable the brushes to be expanded, or pressed, against the walls of the vessel being washed with considerable force. Inasmuch as the action of the brushes is equally efficacious whether they bear directly against the walls of the can or sweep across the same at an angle, it will be seen that in the variable actuation of the brushes that is secured by the means just described, an opportunity is afforded for taking up wear as the ends of the bristle tufts of the brushes grow shorter and shorter with continued use. Thus the brushes as represented in Fig. 3 are shown as they would appear after considerable wear, but they are nevertheless brought into contact with the walls of the can by fully straightening out the arms *d*. Were the brushes shorter, however, it will be evident that by more nearly straightening out these arms the brush will be just as firmly pressed against such walls. The sup-

port C upon which the vessel thus being washed is designed to rest, consists simply of a table or plate, preferably circular in form, rotatably resting upon a bearing provided by the inner end *b*¹² of lever *b*⁷. The under side of this table is provided with a bevel gear *c*² that meshes with a bevel driving pinion *c*³, the latter being mounted upon a driving shaft C' that may be actuated through a pulley *c*⁴, or other equivalent means. To fixedly secure the can or like vessel upon rotary support C a lever C² is provided in the upper portion of the machine frame, this lever bearing upon its under side a rotatable disk *c*⁵ positioned to centrally contact with the bottom of the inverted can when said lever is swung downwardly.

In order that the exterior of the can may be washed simultaneously with its interior, a vertically disposed brush D' is pivotally mounted laterally by the can when secured on such support. This brush is preferably hinged, or oscillatorily mounted, in order to enable it to be accommodated to cans of different diameters, a spring *d*⁴, Fig. 2, being utilized to retain such brush in contact with the can pending the washing operation. A branch connection B² from the pipe B' is disposed laterally contiguous to this brush and is provided with suitable jet openings for supplying the necessary washing liquid required for use in conjunction with this brush.

To catch and conduct away the water as it escapes from the interior of the can, a pan C³, or the like, is mounted just below supporting table C. By arranging that the direction of rotation of the can shall be that indicated by the arrows in Fig. 2, in view of the relative disposition of exterior brush D' and corresponding water supply pipe D², I find that all splashing of water from the outside of the can, even where quite rapidly rotated, is avoided, since the brush catches the water before it has an opportunity to be flung off from the walls of the can. Accordingly this water also drains down into pan C³.

The manner of operation of the machine should be quite evident without further description. In conclusion then, it will suffice to point out that the device here presented is adapted not only to handle vessels of the character in hand expeditiously, but also to effect a thorough cleansing of the same with a minimum quantity of water. Since practically none of such water is wasted a fresh or clean supply may be used with each successive vessel. Furthermore, by employing steam at the conclusion of the washing operation in the manner contemplated, not only is the interior of the vessel thoroughly sterilized, but the brushes also.

Other modes of applying the principle of

my invention may be employed instead of the one explained, change being made as regards the mechanism herein disclosed, provided the means stated by any one of the following claims or the equivalent of such stated means be employed.

I therefore particularly point out and distinctly claim as my invention:—

1. In a device of the character described, the combination with a frame of a substantially horizontally disposed, rotary support adapted to receive the vessel to be washed, such vessel being placed open end down thereon; means for fixedly securing said vessel on said support, such means comprising a lever mounted thereabove, and a member rotatably attached thereto and adapted to be pressed centrally upon the upper end of such vessel; and a relatively stationary expandable brush adapted to be inserted in such vessel.

2. In a device of the character described, the combination with a frame of a substantially horizontally disposed, rotary support adapted to receive the vessel to be washed, such vessel being placed open end down thereon; means for fixedly securing such vessel on said support; a second relatively stationary support extending within such vessel when thus secured; brush members pivotally secured to such stationary support on axes parallel therewith and adapted to be swung outwardly into contact with the interior of such vessel's walls; and means for thus swinging such brush members.

3. In a device of the character described, the combination with a frame of a rotary support adapted to receive the vessel to be washed, such vessel being placed open end down thereon; means for fixedly securing the latter upon said support; a stationary support extending axially within such vessel when thus secured; radially extending arms rigidly mounted upon said support; other arms rotatably mounted thereon; brush members pivotally secured to said first-named arms on axes parallel with said support; and means connecting said brush members with said last-named arms, whereby upon rotation of the latter said brush members may be swung upon their pivotal axes.

4. In a device of the character described, the combination with a frame of a rotary support adapted to receive the vessel to be washed, such vessel being placed open end down thereon; means for fixedly securing the latter upon said support; a stationary liquid supply pipe extending axially within such vessel when thus secured; spaced, radially extending arms rigidly mounted upon said pipe; other arms rotatably mounted upon said pipe; brush members pivotally secured at the ends of said first named arms on axes parallel with said supply pipe; and links connecting said brush members with

said last-named arms, whereby upon rotation of the latter said brush members may be swung upon their pivotal axes.

5. In a device of the character described, the combination with a frame of a rotary support adapted to receive the vessel to be washed, such vessel being placed open end down thereon; means for fixedly securing the latter upon said support; a stationary liquid supply pipe extending axially within such vessel when thus secured, said pipe terminating in a rose; spaced, radially extending pairs of arms rigidly mounted upon said pipe; a sleeve rotatably mounted upon said pipe below the lower pair of said arms; other arms borne by said sleeve and rotatable therewith; brush members pivotally mounted upon the ends of said rigidly mounted arms; links connecting said rotatably mounted arms with said brush members whereby upon rotation of said arms the latter are swung upon their pivotal axes; and means for rotating said sleeve to thus actuate said arms and brush members.

6. In a device of the character described, the combination with a frame of a rotary support adapted to receive the vessel to be washed, such vessel being placed open end down thereon; means for fixedly securing said vessel on said support, such means comprising a lever mounted thereabove, and a member rotatably attached thereto and adapted to be pressed centrally upon the upper end of such vessel; a stationary liquid supply pipe extending axially within such vessel when thus secured, said pipe terminating in a rose; two spaced radially extending pairs of arms rigidly mounted upon said pipe; a sleeve rotatably mounted upon said pipe below the lower of said arms, said sleeve extending through said rotary support; other arms borne by said sleeve and rotatable therewith; brush members provided with arms on their back sides pivotally secured to the ends of said rigidly mounted arms; links connecting said rotatably mounted arms with the arms of said brush members; and a lever mounted upon said sleeve below said rotary support, whereby said sleeve may be rotated to thus actuate said brush members.

7. In a device of the character described, the combination with a frame of a vertically mounted water supply pipe; a sleeve rotatably mounted upon the lower end of said pipe; a table rotatably mounted on said sleeve, said table being provided with a bevel gear on its under side; a driving pinion meshing with such gear; a lever mounted above said support on axes parallel therewith on a transverse axis; a member rotatably attached to said lever and adapted to be centrally pressed upon a vessel placed upon said table; two spaced, radially extending pairs of arms rigidly mounted upon

said water supply pipe; other arms borne by said sleeve and rotatable therewith; brush members pivotally mounted upon the ends of said rigidly mounted arms; links connecting the arms borne by said sleeve with said brush members; and a lever mounted upon said sleeve below said table, whereby said sleeve may be rotated to swing said brush members.

- 10 8. In a device of the character described, the combination with a frame of a vertically mounted water supply pipe, said pipe terminating in a rose; a steam supply pipe lying within said water supply pipe and extending thereabout; a sleeve rotatably mounted upon the lower end of said pipe; a table rotatably mounted on said sleeve, said table being provided with a bevel gear on its under side; a driving pinion meshing 20 with such gear; a lever mounted above said support on a transverse axis; a member rotatably attached to said lever and adapted to be centrally pressed upon a vessel placed upon said table; two spaced, radially extending pairs of arms rigidly mounted upon 25 said water supply pipe; other arms borne by said sleeve and rotatable therewith; brush members pivotally mounted upon the ends of said rigidly mounted arms; links connecting the arms borne by said sleeve with said brush members; and a lever mounted upon 30 said sleeve below said table, whereby said sleeve may be rotated to swing said brush members.
- 35 9. In a device of the character described, the combination with a frame of a substantially horizontally disposed, rotary support adapted to receive the vessel to be washed; means for fixedly securing the latter open 40 end down upon said support; a water-sup-

ply pipe extending centrally within said vessel when thus secured; a steam-supply pipe lying within said water-supply pipe and extending thereabove; and a brush borne by said water-supply pipe and adapted to be 45 pressed against the walls of said vessel.

10. In a device of the character described, the combination of a brush member pivotally mounted eccentrically of the axis of the vessel to be washed and adapted to be swung 50 into contact with the interior wall of such vessel, said brush member comprising a portion disposed to thus contact with the body of the vessel and another portion, radially inset with respect to such first portion, to 55 contact with the neck of the vessel, such inset portion being also laterally offset with respect to the other portion, substantially as described.

11. In a device of the character described, the combination of an elongated brush member pivotal about a longitudinally disposed axis other than that of the vessel to be washed so as to be adapted to swing outwardly into contact with the interior wall of 65 such vessel, said brush member comprising a portion disposed to thus contact with the body of the vessel and another portion, radially inset with respect to such first portion, to contact with the neck of the vessel, such 70 inset portion being also laterally offset with respect to the other portion on the side folded in when the brush is collapsed, substantially as described.

Signed by me this 7th day of May, 1907. 75

JAKE L. RANNEY.
